UNITED STATES PATENT OFFICE

ISAIAH A. EAKINS, OF PLEASANTON, TEXAS, ASSIGNOR TO GENERAL AMERICAN TANK CAR CORPORATION, OF CHICAGO, ILLINOIS, A CORPORATION OF WEST VIRGINIA

SUPPORTING STRUCTURE

Application filed May 5, 1930. Serial No. 449,931.

My invention relates, more particularly, to the supporting, on vehicles, of running boards or platforms, as for example, and especially, running boards on tank cars and platforms at tank car domes.

One of my objects is to provide for the supporting of running boards or platforms without requiring the boring of holes in the boards of which they are commonly constructed, the common practice being to secure the boards in place by means of bolts extending through the boards which is objectionable not only because of the cost of construction and the labor required for installation, but also because the boring of holes in the boards renders the boards very susceptible to decay.

Another object is to provide inexpensive supporting means for the boards and requiring the use of the minimum number of bolts or other devices for securing them in place.

Another object is to reduce to as great a degree as possible, the cost of maintaining structures such as those above referred to, in operative and safe condition.

Another object is to provide for the use of short lengths of material for the running boards; and other objects as will be manifest from the following description.

Referring to the accompanying drawings: Figure 1 is a view in side elevation of a tank car equipped with a running board structure and a platform structure constructed in accordance with my invention.

Figure 2 is a plan view of the structure shown in Fig. 1, with the tank at one end of the car removed to disclose details of structure which would otherwise be obscured.

Figure 3 is a view in end elevation of the underframe of the car of Fig. 1.

Figure 4 is a broken enlarged sectional view taken at the line 4—4 on Fig. 2 and viewed in the direction of the arrows.

Figure 5 is a broken enlarged sectional view taken at the line 5—5 on Fig. 2 and viewed in the direction of the arrows, this view showing the tank in place.

Figure 6 is an enlarged bottom plan view of one of the similar corner portions of the running board structure of the car.

Figure 7 is an enlarged broken sectional

view taken at the line 7 on Fig. 2 and viewed in the direction of the arrow.

Figure 8 is an enlarged broken sectional view taken at the line 8 on Fig. 2 and viewed in the direction of the arrow. 55

Figure 9 is an enlarged broken sectional view taken at the line 9—9 on Fig. 1 and viewed in the direction of the arrow; and

Figure 10, a broken enlarged section taken at the line 10—10 on Fig. 2 and viewed in 60 the direction of the arrows.

Referring to the particular illustrated embodiment of my invention, the underframe of the car is represented generally at 10 and the tank portion thereof at 11 the latter being 65 provided with the usual dome structure represented at 12.

The underframe 10 is of the so-called center sill type, the center sill thereof being represented at 13 and shown as provided with 70 body-bolster-forming sections 14 secured to the center sill in pairs at opposite ends of the center sill, the tank 11 being supported adjacent its ends on saddle blocks interposed between the tank and the underframe at the 75 bolster section 14, as represented by the saddle blocks 15 at one of the bolster-forming sections 14.

Any suitable means for anchoring the tank 11 to the underframe may be provided, the structure being shown as provided with tank bands 16 secured to the underframe and partially encircling the tank 11 in accordance with common practice. 80

The underframe 10 is shown as provided with a running board structure represented generally at 17 and extending entirely around the tank 11, the portions of the running board structure at opposite ends of the tank being shown as each formed of a single board or plank 18. The running board structure 17 at opposite sides of the car and represented at 19 may each be formed of a single length of board or plank or a plurality of end-to-end disposed plank or boards, as desired. 90

In the arrangement shown the side portions 19 of the running boards are shown as supported between their ends on cross bearers 20 shown as located in spaced apart relation 95 at opposite sides of the center of the car. 100

The running board portions 18 at the ends of the car are shown as supported on, and secured by, rivets 21 to a U-shaped bracket 22 secured to the center sill 13.

5 The means located between the ends of the underframe for securing the side portions 19 of the running board in place on the underframe, comprise clip-devices 23 each formed of a pair of nested sections 24 and 25 made 10 of sheet metal.

10 The clip sections 24 comprise inverted U-shaped members 26, the depending leg portions of which are represented at 27 and 28, and a tongue portion 29. The clip sections 24 are applied to the outer ends of the cross bearers 20 to the position shown in the drawings in which position the tongues 29 extend into the upwardly opening channels of the cross bearers 20 to the bottom portions 20 of which the tongues 29 are secured as by rivets 30, the leg portions 28 of these clip sections being slotted to adapt them to fit over the flanges of the cross bearers as shown. Each clip section 25 is of inverted U-shaped 25 and straddles at its legs 31 the clip section 24. The running boards are located between these clip sections, the latter being secured to each other by any suitable means extending through their legs as for example the rivets 30, it being preferred that the legs of one of these clip sections be vertically slotted to receive the rivets and permitting of the securing of these clip sections together about running boards of different thicknesses. 35 In Fig. 10 the vertical slots referred to are shown as in the legs 27 and 28 as represented at 33.

40 In the construction shown the ends of the running board portions 19 are shown as connected with the end sections 18 of the running board by clip devices of the same general construction as that above described.

45 These clip devices are represented at 34 and each comprises nested sections 35 and 36. Each lower section 35 is of general inverted U-shape presenting a substantially horizontal plate portion 37, parallel depending legs 38 and 39, a depending leg 40 at its outer end, and a tongue portion 41 provided with an upturned flange 42. Each clip section 36 is also 50 of general inverted U-shape presenting the parallel legs 43 and 44 and a depending flange 45 at one end. The clip sections described are assembled with the running board 55 portions 18 and 19 at the corners of the running board structure into the position shown, the clip sections 35 being positioned against the under side of these corner portions as shown and the clip sections 36 applied to the 60 upper surfaces of these corner portions, the sections 35 thus becoming nested with the sections 36, with the running board portions interposed therebetween. In this position of the parts described the running board portions 65 19 are embraced between the legs 43 and

44 of the clip section 36 and the running board portions 18 are embraced between the flange portions 45 of the clip sections 36 and the upwardly extending tongues 42 of the sections 35. The clip sections are secured together by any suitable fastening means extending through the depending members of the clip portions, as for example by the rivets represented at 46, the holes in the depending portions of one section of each clip through 70 which the rivets extend, being preferably vertically elongated to adapt them to boards of different thicknesses as explained above in connection with the clip devices 23.

75 In the particular construction shown the rivets 46 at the outer sides of the running board portions 19 are connected together as represented at 47 to provide handholds at the opposite sides of the car at both ends thereof.

80 The clip devices 34 may, or may not, be secured directly to the underframe of the car, as desired. However, in the particular construction shown means are provided for so supporting these clip devices, the means shown comprising bars 48 connected with the center sill and extending laterally outwardly therefrom to the outer ends of which the clip sections 35 are riveted.

85 Where the distance between the clip devices 23 and the clip devices 24 is such that objectionable vibration of the running board portions 19 may result, I prefer to provide means for preventing such vibration these means in the particular construction shown comprising clips 49 shown as secured to the bolster sections 14 as by rivets represented at 50 and having portions 51 which overlie the upper surfaces of the running board portions 19.

90 In the particular construction shown the platform on which the workmen stand when anything is to be done at the dome portion 52 of the car, is constructed in accordance with 100 my invention.

95 The platform portion above referred to and represented generally at 53 is formed of a 110 plank 54 held in place by a clip device formed of a lower section 55 and upper sections 56 and 57 nested with the clip section 55. The clip section 55 is of general inverted U-shape, the depending legs of which are represented at 115 58 and 59, this section being flatwise secured at its plate portion 60 to a pair of bracket members 61 secured, as indicated at 62 and 63, to the tank 11. The clip sections 56 and 57 are located at the ends of the clip section 55 and are of general inverted U-shape and each presenting the spaced apart legs 64 and 65 and a depending crosswise extending flange 66. The platform plank 54 120 is secured in position by applying the clip sections 56 and 57 to the position shown in the drawings the end flanges 66 extending across the ends of the plank section 54 to prevent the lengthwise displacement of the latter, the 130

clip sections being secured together by rivets 67 and 68 extending through the adjacent depending portions of the clip sections, the bolt holes in either the clip section 55 or the clip

5 sections 56 and 57 being preferably vertically elongated for the reason above explained.

It will be understood from the foregoing that by providing clip devices in accordance with my invention, it is not necessary to bore

10 holes in the planks thereby eliminating the above referred to objections incident thereto. Furthermore, the number of fastening devices required to hold the planks securely in

15 operative position is reduced to the minimum as compared with structures as hitherto provided; adjustments or substitution of parts of the structures formed of the planks much less frequently required to be made, with consequent reduction in expense for maintenance,

20 and in the case of the running board structure the portions thereof at each side of the car may be made of relatively short sections of plank the joints between which would be located at the clip devices 23 or certain of

25 them, depending upon the conditions.

While I have illustrated and described certain particular embodiments of my invention, I do not wish to be understood as intending to limit it thereto as the same may be variously modified and altered and the invention embodied in other forms of structure, without departing from the spirit of my invention.

What I claim as new and desire to secure by Letters Patent is:

35 1. In combination, planks disposed at an angle to each, and means for connecting said planks together at their adjacent ends comprising members each of general U-shape and nested together, said planks being interposed between said members, the leg portions of said members being located at opposite edges of one of said planks, means engaging the leg portions of said members for securing them together, the other of said planks end-wise abutting the leg portion of one of said members, and one of said members having an angularly-disposed portion lapping the outer edge of said last-referred to plank.

40 2. In combination, planks disposed at an angle to each, and means for connecting said planks together at their adjacent ends comprising members each of general U-shape and nested together, said planks being interposed between said members, the leg portions of said members being located at opposite edges of one of said planks, means engaging the leg portions of said members for securing them together, the other of said planks end-wise

45 abutting the leg portion of one of said members, one of said members having an angularly-disposed portion lapping the outer edge of said last-referred-to plank, and a tongue on one of said members extending at the inner edge of said last-referred-to plank.

50 3. In combination, planks disposed at an angle to each, and means for connecting said planks together at their adjacent ends comprising members each of general U-shape and nested together, said planks being interposed between said members, the leg portions of said members being located at opposite edges of one of said planks, means engaging the leg portions of said members for securing them together, the other of said planks end-wise

55 abutting the leg portion of one of said members, one of said members having an angularly-disposed portion lapping the outer edge of said last-referred-to plank and secured together.

60 4. A plank-securing structure comprising a plank-supporting member having depending spaced apart legs, inverted U-shaped members at the opposite ends of said first-named member with their legs flatwise opposing the legs of said first-named member, the plank being interposed between said supporting member and said second-named members, and means securing said members together at said flatwise-opposed legs.

65 5. A plank-securing structure comprising a plank-supporting member having depending spaced apart legs, inverted U-shaped members at the opposite ends of said first-named member with their legs flatwise opposing the legs of said first-named member, the plank being interposed between said supporting member and said second-named members, means securing said members together at said flatwise-opposed legs, and means on certain of said members lapping the ends of said plank.

70 6. A plank-securing structure comprising a plank-supporting member having depending spaced apart legs, inverted U-shaped members at the opposite ends of said first-named member with their legs flatwise opposing the legs of said first-named member, the plank being interposed between said supporting member and said second-named members, means securing said members together at said flatwise-opposed legs, and means on said second-named members lapping the ends of said plank.

75 7. In a tank-car, the combination of its underframe having channel-shape cross-bearers between its ends, a tank on said underframe, a running-board at the side of said tank, and means for securing said board in place comprising clip-devices extending crosswise above said cross-bearer and each formed of members of inverted general U-shape nested together with the board interposed therebetween, one member of each pair being connected with the ends of said cross-bearers, said devices being slotted and straddling said cross-bearers, and means engaging the leg-portions of said members for securing them together.

80 8. In a tank-car, the combination of its underframe having cross-bearers between its

ends, a tank on said underframe, a running board surrounding said tank, and means for securing said running-board in place comprising clip-devices at said cross-bearers and 5 at the corners of said running board each comprising members of general U-shape nested together with the plank forming said board interposed therebetween, said members at said corners embracing both the end 10 and side members of said running board, and means engaging the leg-portions of said members for securing them together.

9. In a tank-car, the combination of its underframe having cross-bearers between its 15 ends, a tank on said under-frame, a running board surrounding said tank, and means for securing said running-board in place comprising clip-devices at said cross-bearers and at the corners of said running board each 20 comprising members of general U-shape nested together with the planks forming said board interposed therebetween, and means engaging the leg-portions of said members for securing them together, certain 25 of said members having portions lapping the outer edges of those planks of said running board which extend across the ends of the car.

10. In a tank car, the combination of its 30 underframe having channel-shape cross-bearers between its ends, a tank on said underframe, a running-board at the side of said tank, and means for securing said board in place comprising clip devices extending 35 crosswise above said cross-bearers and each formed of members of inverted general U-shape nested together with the board interposed therebetween, one member of each pair having a tongue extending into the channels 40 of said cross-bearers and secured in flatwise position therein, said devices being slotted and straddling the upwardly extending flange portions of said cross-bearers, and means engaging the leg portions of said members 45 for securing them together.

11. In a tank car, the combination of its 50 underframe having cross-bearers between its ends, a tank on said underframe, a running board at the side of said tank, and means for securing said board in place comprising clip devices extending crosswise of, and resting upon, said cross-bearers, each of said devices being formed of members of general U-shape 55 nested together with the board interposed therebetween, one member of each pair being connected with the ends of said cross-bearers and means engaging the leg portions of said members for securing them together.

12. In a tank car, the combination of its 60 under frame having cross-bearers between its ends, a tank on said underframe, a running board at the side of said tank, and means for securing said board in place comprising clip devices extending crosswise of, and resting upon, said cross-bearers, each of 65

said devices being formed of members of general U-shape nested together with the board interposed therebetween, one member of each pair having a tongue which extends laterally, and crosswise, of said device and at which tongues said devices are connected with said cross-bearers, and means engaging the leg portions of said cross members for securing them together.
